UNITED STATES PATENT OFFICE

168,912

COMBINED COAT HANGER AND BRUSH

William B. Schaefer, Cincinnati, Ohio

Application December 10, 1952, Serial No. 22,611

Term of patent 14 years

(Cl. D80—8)

To all whom it may concern:

Be it known that I, William B. Schaefer, a citizen of Austria, residing at Cincinnati, in the county of Hamilton, and State of Ohio, have invented a new, original, and ornamental Design for a Combined Coat Hanger and Brush, of which the following is the specification, reference being had to the accompanying drawing forming a part hereof.

Referring to the figures of the drawing:

I claim:

The ornamental design for a combined coat hanger and brush, as shown.

WILLIAM B. SCHAEFER.
